US00D570289S

(12) **United States Design Patent** (10) Patent No.: **US D570,289 S**
Obikane (45) Date of Patent: **** Jun. 3, 2008**

(54) **ELECTRICAL CONNECTOR**

(75) Inventor: **Hiroaki Obikane**, Tokyo (JP)

(73) Assignee: **Japan Aviation Electronics Industry, Limited**, Tokyo (JP)

(**) Term: **14 Years**

(21) Appl. No.: **29/270,804**

(22) Filed: **Jan. 3, 2007**

(30) **Foreign Application Priority Data**

Jul. 5, 2006 (JP) 2006-017686

(51) **LOC (8) Cl.** 13-03

(52) **U.S. Cl.** **D13/147**

(58) **Field of Classification Search** D13/133, D13/146–147, 154, 184; D14/432–433, D14/435–436, 438; 439/64, 79, 108, 260, 439/159–160, 325–326, 329, 394–395, 607–610, 439/629–630

See application file for complete search history.
